UNITED STATES PATENT OFFICE.

BARTOLOMEO DELLA LIBERA, OF SEVESO SAN PIETRO, ITALY, ASSIGNOR TO THE FIRM FRATELLI SCHWARZENBACH & CO., OF SEVESO SAN PIETRO, ITALY.

SHUTTLE CHANGE.

Application filed February 26, 1923. Serial No. 621,390.

To all whom it may concern:

Be it known that I, BARTOLOMEO DELLA LIBERA, a subject of the King of Italy, residing at Seveso San Pietro, Italy, have invented a certain new and useful Improvement in Shuttle Changes, of which the following is a specification, reference being had therein to the accompanying drawing.

This invention relates to a device for changing the shuttle in the batten of weaving looms, in which a shuttle-box may be divided into two super-imposed compartments by a movable partition plate, a switch device being provided in front of the shuttle-box, the said switch (after the shuttle coming from the lower compartment and placed in the path of the picker stick is shot) automatically taking up a position that will allow the shuttle on its return travel to reach the upper compartment of said shuttle-box which in the meantime has dropped its shuttle into the lower compartment after the movable partition plate has temporarily taken up a position allowing this second shuttle to drop into the said lower compartment and be shot therefrom.

This device may be fitted for instance to looms in which two shuttles filled with different kinds of yarn come alternately into operation.

The accompanying drawings exemplify a construction according to the present invention.

Fig. 1 is a side elevation of the loom with the batten in one of its end positions.

Fig. 1^a is a section on a horizontal plan through a detail.

Fig. 2 is a partial front elevation of the left hand side of the loom.

Fig. 3 is a plan of Fig. 2.

Figs. 4 and 5 are details on an enlarged scale showing the relative position of certain movable parts.

Figs. 6 to 9 are explanatory of the working of the shuttle-changing device.

Fig. 10 is a partial view of the rear of the lay.

Fig. 11 is a side elevation of the front part of the loom showing the batten in one of its intermediate positions.

Figs. 12 to 14 illustrate the operative connection between the shuttle-changing device and the stop-motion of the loom.

The gear wheel 1 meshing with the gear

wheel 2 revolves at twice the speed of the latter and is keyed to the crank 3 oscillating the batten 5 about a horizontal shaft 6 through a pair of links 4. The somewhat short shuttle-operating picker stick 7 is arranged on one side of the loom and is provided with a foot connected to a suitable picker lug 10 by means of a member 9. The picker lug is fast on the shaft 11 and is periodically operated by the picker lug shaft of the loom for the purpose of actuating the picker stick; the oppositely arranged picker stick 12 is illustrated in Figs. 6 to 9. One of the ends of a bent rail 13 is secured to the picker lug 10 of the picker stick 7, the other end forming the pivot point 70 of a rod 14, the pivot pin of which is in line with the axis of the shaft 6 of the batten. The other end of the rod 14 is pivoted to a lever 15 mounted on a support 16 secured to the batten and carrying another lever 17. A pin 18 on the lever 15 co-operates with a cam face cut on the lever 17 the other end of which is secured to a rod 19 mounted in a guide 20 of the batten and operatively connected to a cam member 21 adapted to oscillate on the batten and co-operate with the switch 23 through a pin 22, the pivot pin of the said switch being located in a recess of the batten. The switch is fitted with a leaf spring 23^a forming a stop for the cam member 21. An angle piece 24 acts as a stop for the switch when the latter is in its operative position.

The shuttle-box A at one end of the batten carries a partition plate 25 pivoted at 26 and connected to a controlling lever 29 by the articulation 27, 28. The said controlling lever is mounted on the shaft 6 of the batten and is operatively connected by means of a link 30 to a lever 31 pivoted on a pin 32 integral with the frame of the loom. A spring 33 in tension tends to pull the controlling lever 29 towards the batten, so that the roller 34 of the lever 31 is pressed against a double cam 35 keyed to the shaft 100 of the gear wheel 2.

When the partition plate 25 is oscillated about the pin 26 by connection 27, 28, rod 29, link 30, lever 31 and cam 35 and enters the shuttle-box A, the latter is divided into an upper and lower shuttle compartment (Fig. 4). The upper compartment is provided on one side with the usual spring-

controlled brake member 36 with pivot pin 36' and with an upper, spring-controlled brake lever 37; a spring buffer 38 is also provided for the purpose of receiving the 5 shuttle point. A spring 39 pushes the rod 19 towards the cam member 21. The bent pin 40 is secured to the brake member 36.

The shuttle-changing device works as follows:

- 10 It will be assumed that the two shuttles I and II are in position in the box A and separated from one another by the partition plate 25 after it has moved inwards (Fig. 6), the batten oscillating backwards. The 15 shuttle I in the lower compartment of the box A is shot by the picker stick 7 at a predetermined time into the oppositely arranged shuttle-box B of the batten a few moments before the switch plate 23 had 20 completely entered in its recess in the batten, the said switch plate being raised thereafter (Fig. 7). The forward oscillation of the batten now causes the partition plate 25 to move out of the said batten so that the 25 shuttle II is now deprived of its support. The partition plate at the end of its movement strikes the bent pin 40 so that the brake member 36 is thrown into its inoperative position against the action of its spring 30 (Figs. 3, 5, 14); the shuttle II is now set free and drops by gravity into the lower portion of the box A (Fig. 8). The partition plate 25 is now swung into the batten again to receive the shuttle I shot back into 35 the box A by the picker stick 12 and upwardly directed by the switch-plate 23 before reaching the said box A (Fig. 9). The cycle of operations is repeated at every reciprocated oscillation of the batten, the shuttles I and II alternately replacing one another.

The switch-plate 23 is operated by the picker lug 10 of the picker stick 7. When the said lug moves upwardly, the rod 19 45 (while the member 9 is tensioned) is moved backwards against the action of the spring 39 through the parts 13, 14, 15 and the action of the pin 18 on the lever 17, so that the cam member 21 leaves the pin 22 of the 50 switch plate 23. The latter completely enters its recess of the batten by gravity or is moved positively thereinto to the cam member 21 impinging on the leaf spring 23a. Owing to the pressure exerted by the said 55 cam member 21 on the said spring 23a the switch plate 23 is kept in the position in which its upper edges are flush with the surface of the path of travel of the shuttle so that the direction of motion of the latter 60 is not altered when gliding over the switch-plate. The picker stick 7 becomes now operative for shooting the shuttle ready for that purpose. When the said picker stick 7 resumes its initial position the pin 18 is moved 65 upwardly so that the spring 39 now rendered

operative thereby, moves the rod 19 to actuate the cam member 21; the latter engages the pin 22 with its inclined face to raise the switch-plate 23. A weaving-loom fitted with the above described shuttle-changing 70 device may be run at a higher number of revolutions than when the shuttles are alternately replaced by continuously moving a drop-box. In the present apparatus the shuttle is changed in the box A when the 75 shuttle just shot is under way to the box B and back; when the said shuttle is back in the box A the second shuttle, which in the meantime became ready in position, may be immediately shot, as there is no further 80 changing movement to be performed.

The following steps are taken in order to cause the shuttle-changing device to co-operate with the stop motion of the loom to render the latter operative when a shuttle 85 fails in its travel or does not complete the latter.

A rod 41 arranged parallel to and under the batten is provided at both its ends with two upwardly extending feeler arms 42 and 90 43, and carries two strikers 44, one for each shuttle-box. A resilient stem 45 is placed in each of the paths of the strikers 44, the stems 45 being interconnected so that the movement of the one is followed by the 95 other. One of the said stems has a laterally-extending arm carrying a set screw 46 operated by the resilient stems and adapted to operate the resilient stop-motion lever 47 of the loom when the said lever leaves its 100 position of rest, as shown in full lines in Fig. 1a and moves into the position shown in dotted lines, whereby the loom is thrown out of operation. The feeler arm 43 of the rod 41 is within the sphere of action of 105 the spring-loaded brake member 48 of the shuttle-box B; the feeler arm 42 is within the sphere of action of a lever 49 mounted on the partition plate 25 of the shuttle-box A. A vertical striker-pin 50 is fitted to the 110 brake member 36.

Assuming a position of the parts in which the batten is swung forwards and the partition plate 25 is in the batten, the shuttle on entering the upper compartment of the box 115 A pushes back the brake member 36 projecting into its path (Fig. 12), so that the striker pin 50 of the brake member presses the lever 49 against the feeler arm 42 (Fig. 13). As a result, the rod 41 is rotated so 120 that the strikers 44 are moved upwards against the action of springs 51, and on the batten being further oscillated, come in their inoperative position with their free ends above the resilient stems 45. The partition 125 plate begins to move out of the batten immediately after the shuttle has left the lower compartment of the box A so that the lever 49 comes into a position relatively to the parts 50 and 42 so that the feeler arm 42 is 130

released (Fig. 14). The strikers 44 now move downwards and by coming into contact with stops 52 of the resilient stems 45, the latter are bent, the stop-motion lever 47 being released and the loom stopped if the shuttle fails to complete its travel. If however the shuttle correctly reaches the opposite box B the brake member 48 is thrust out of the path of the shuttle. The strikers 44 are thus moved upwards in their idle position by the feeler arm 43 and the stop-motion lever 47 is not released. Should the returning shuttle not reach the upper compartment of the box A and therefore the brake member 36 not be thrust out of the path of the shuttle as required, the strikers 44 which in the meantime have sunk, remain in their position and thus release the stop-motion lever 47 through the resilient stems 45 for the purpose of rendering the loom inoperative.

I claim:

1. A device for changing the shuttle in the batten of a weaving loom, comprising two shuttle boxes on said batten, a movable partition plate in one of said shuttle boxes adapted to divide said shuttle box into two superimposed compartments, switch means provided in front of the latter shuttle box and adapted to cause a returning shuttle to reach the upper of said compartments, means adapted to automatically operate said switch means, means to operate said movable partition plate to permit the shuttle delivered into the upper compartment to drop into the lower compartment, and a shuttle operating device.

2. A device for changing the shuttle in the batten of a weaving loom, comprising two shuttle boxes on said batten, a movable partition plate in one of said shuttle boxes adapted to divide said shuttle box into two superimposed compartments, a switch-plate pivoted in a recess of said batten in front of the latter shuttle box and adapted to cause a returning shuttle to reach the upper of said compartments, means adapted to operate said movable partition plate to permit the shuttle delivered into the upper compartment to drop into the lower compartment, and a device adapted to operate the shuttles and said switch-plate.

3. A device for changing the shuttle in the batten of a weaving loom, comprising two shuttle boxes on said batten, a movable partition plate in one of said shuttle boxes adapted to divide said shuttle box into two superimposed compartments, a switch-plate pivoted in a recess of said batten in front of the latter shuttle box and adapted to cause a returning shuttle to reach the upper of said compartments, means adapted to operate said movable partition plate to permit the shuttle delivered into the upper compartment to drop into the lower compartment.

ment, a shuttle-operating device, and a link connection between said shuttle-operating device and said switch-plate.

4. A device for changing the shuttle in the batten of a weaving loom, comprising two shuttle boxes on said batten, a movable partition plate in one of said shuttle boxes adapted to divide said shuttle box into two superimposed compartments, a switch-plate pivoted in a recess of said batten in front of the latter shuttle box and adapted to cause a returning shuttle to reach the upper of said compartments, means adapted to operate said movable partition plate to permit the shuttle delivered into the upper compartment to drop into the lower compartment, a shuttle operating device, an oscillating cam member, a link interposed between said oscillating cam member and said shuttle-operating mechanism, and a pin on said switch plate and co-operating with said oscillating cam member for periodically actuating said switch-plate.

5. A device for changing the shuttle in the batten of a weaving loom, comprising two shuttle boxes on said batten, a movable partition plate in one of said shuttle boxes, pivoted to said batten and adapted to divide said shuttle box into two superimposed compartments, switch means provided in front of the latter shuttle box and adapted to cause a returning shuttle to reach the upper of said compartments, means adapted to automatically operate said switch means, means to operate said movable partition plate to permit the shuttle delivered into the upper compartment to drop into the lower compartment, and a shuttle-operating device.

6. A device for changing the shuttle in the batten of a weaving loom, comprising two shuttle boxes on said batten, a movable partition plate in one of said shuttle boxes, pivoted to said batten and adapted to divide said shuttle box into two superimposed compartments, a switch-plate provided in front of the latter shuttle box and adapted to cause a returning shuttle to reach the upper of said compartments, a spring loaded brake member adapted to act upon the shuttle shot into the upper compartment, an operative connection between said spring loaded brake member and said partition plate to cause the former to partake of the movement of the partition plate, means adapted to operate said partition plate to permit the shuttle delivered into the upper compartment to drop into the lower compartment, and a shuttle-operating device.

7. A device for changing the shuttle in the batten of a weaving loom, comprising two shuttle boxes on said batten, a movable partition plate in one of said shuttle boxes, pivoted to said batten and adapted to divide said shuttle box into two superimposed compartments.

parts, a switch plate provided in front of the latter shuttle box and adapted to cause a returning shuttle to reach the upper of said compartments, a spring loaded brake member adapted to act upon the shuttle shot into the upper compartment, an operative connection between said spring loaded brake member and said partition plate to cause the former to partake of the movement of the partition plate, means adapted to operate said partition plate to permit the shuttle delivered into the upper compartment to drop into the lower compartment, a shuttle-operating device, a stop-motion device and means operatively connected to said brake member for actuating said stop-motion device when the shuttle does not correctly reach the upper compartment.

8. A device for changing the shuttle in the batten of a weaving loom, comprising two shuttle boxes on said batten, a movable partition plate in one of said shuttle boxes, pivoted to said batten and adapted to di-

vide said shuttle box into two superimposed compartments, a switch plate provided in front of the latter shuttle box and adapted to cause a returning shuttle to reach the upper of said compartments, a spring loaded brake member adapted to act upon the shuttle shot into the upper compartment, an operative connection between said spring loaded brake member and said partition plate to cause the former to partake of the movement of the partition plate, means adapted to operate said partition plate to permit the shuttle delivered into the upper compartment to drop into the lower compartment, a lever on said partition plate, a strike-pin on said brake member actuating said lever, said lever being adapted to actuate said stop-motion device when the shuttle does not correctly reach the upper compartment.

In testimony whereof I affix my signature.

BARTOLOMEO DELLA LIBERA.
